Specification of Letters Patent.

Patented Feb. 10, 1914.

Application filed November 29, 1912. Serial No. 733,958.

To all whom it may concern:

Be it known that I, CHARLES D. McCARTY, a citizen of the United States of America, and resident of Wheeling, county of Ohio, and State of West Virginia, have invented 5 certain new and useful Improvements in Plumbs, of which the following is a specification.

This invention relates to improvements in 10 plumbs for carpenters' and joiners' use, and more particularly to a novel form of plumb rule.

The primary object of the invention is to provide an extremely simple and comparatively inexpensive tool whereby upright walls, shafts, newels, pilasters, and the like may readily be plumbed.

A further object is to provide a device which is specially adapted for use in plumb- 20 ing surfaces between projecting ledges, fillets, or moldings, or in close places the plumbing of which is ordinarily attended with more or less difficulty. And a still fur- 25 ther object is to provide a tool of the char- acter mentioned which is of such size as to permit of its being conveniently carried either in a pocket or in any ordinary tool- 30 kit.

With these and other objects in view, the 35 invention resides in the features of construction, arrangement of parts and combinations of elements which will hereinafter be exemplified, reference being had to the accompanying drawings, forming a part of this specification, in which—

Figure 1 is a rear elevation of the invention; Fig. 2 is a horizontal section of the same; Fig. 3 is a front elevation of the 40 same; and Fig. 4 is a perspective view of the invention, showing it applied to the plumbing of a newel post.

Referring to said drawings, in which like designating characters distinguish like parts throughout the several views—1 indicates 45 the body portion of a gage-like clamp which is mortised on its rear face to form oppositely disposed shoulders 1^a and 1^b which define the ends of a space adapted for receiving a bar, scantling, or other suitable 50 piece of material, as 2, which may or may not be irregular in shape, as will hereinafter be explained. Extending through the angularly disposed outer end 3 of the clamp is a finger-operated jack-screw 4, preferably pro- 55 vided with a milled head 5, the presser shoe 6 of which is adapted to exert clamping

pressure on the outer edge of the piece 2 whereby the clamp is rigidly attached to said piece. A forwardly projecting lip or lug 7 is formed upon, or is carried by, the 60 front face of the clamp, and provided therein is a notch or kerf 8 adapted for receiving the line 9 of a plumb-bob 10. The inner end of the clamp has a plain squared face 11 adapted for seating abutting engagement 65 with the upright surface to be plumbed.

In practice, two of the clamps just described are employed, the same being clamped, as described, upon a scantling or other suitable piece of material of appropriate length. Owing to the fact that the notches or kerfs in the lugs 7 of said clamps are located at precisely equal distances from the inner, or squared ends, of the clamps, it will be obvious that when the scantling is placed 70 upright with said squared ends seated firmly against the surface to be plumbed, the vertically suspended plumb line 9 supported in the kerf of the uppermost clamp, as by a knot 12, should hang directly in the kerf of 75 the lowermost clamp.

It will be noted that the device is specially adapted for use in close places, as between projecting ledges, moldings, or the like, where pieces 2 of any considerable length 80 may not be employed because of interference from said projections, it being only necessary to select a piece of any convenient material having a length which may be interposed between the outstanding projections 85 and to attach the two clamps thereto, as described, and to suspend a plumb line from the uppermost clamp, whereupon the plumb-ing operation may be quickly and conveniently performed. When it is desired to 90 plumb a high plain-faced wall, shaft, or the like, the same may be readily accomplished from below by attaching the clamps to the opposite ends of a scantling having the requisite length and elevating the same by hand 95 to proper position.

The upper and lower clamps are preferably made identical in size and form, rendering them interchangeable.

As is obvious, the bar or scantling 2 need 105 not have straight or regular sides or edges; an object had in view in the production of the present invention being to permit of the use of any form or shape of bar or like de- 110 vice which may be found close at hand to which the clamps may be attached, thus avoiding the necessity of having to employ

a straight or specially formed or shaped piece of material, as is usually required.

Having thus described my invention, what I claim as new, and desire to secure by Letters Patent, is—

A plumb-rule comprising a bar, a pair of clamps removably mounted in fixed position on said bar, said clamps having their inner ends squared and equidistant from the corresponding edge of said bar, and projecting

lugs carried on the front faces of said clamps, said lugs having notches provided therein equidistant from the squared ends of the clamps.

In testimony whereof, I affix my signature 15 in presence of two subscribing witnesses.

CHARLES D. McCARTY.
